UNITED STATES PATENT OFFICE.

WILLIAM G. WAGENHALS, OF DETROIT, MICHIGAN.

ELECTRIC MOTOR.

Application filed April 8, 1927. Serial No. 181,952.

The present invention relates to electric motors and more especially to small power motors for operation of advertising devices, toys and the like.

5 Among the objects of the invention is a motor which shall be economical to produce and assemble and simple to adjust and operate.

Other objects will readily appear to those skilled in the art upon reference to the following description and accompanying drawing in which:—

Fig. 1 is a plan view of the motor;

Fig. 2 is a side elevation; and

15 Fig. 3 an end elevation thereof.

As indicated the motor will preferably be mounted on a base 10 and comprise a frame member 11 which is in the form of a longitudinal lower part 12 adapted to be secured 20 to base 10 and having four upright portions 13, 14, 15 and 16. Uprights 13 and 14 are intermediate the ends of part 12 and are provided with openings near the bottom for the passage therethrough of a core 20 which 25 supports between 13 and 14 a coil 21 preferably wound for ordinary house lighting current. The core 20 being preferably fixed in place by a set screw 22.

Near the top of uprights 13 and 14 is a 30 cross member 23 joining the uprights and furnishing means for the support of an insulating shelf 24, the supporting means being, for example, a laterally extending flat lug 25 upon which the shelf 24 is secured by 35 screw 26. In shelf 24 are two binding posts 27 and 28 to which may be secured the current leads 29.

Upright member 15 is preferably provided 40 with an upper extended surface 35 upon which is secured as by screw 37 another insulating shelf 36, and at one end of this shelf is mounted a stop piece 38 having an elevated horizontal arm 39 in which is an adjustable stop screw 40. At the other end 45 or shelf 36, is fixed a spring arm 45 extending longitudinally of the shelf to beneath stop screw 40. This spring arm 45 carries one of a pair of contacts indicated at 46, the other 47 of the pair being carried on the 50 shelf 36 and being electrically connected to a binding post 48.

Mounted in suitable bearings in the upper part of uprights 13 and 14 is a shaft 55 which extends a short distance beyond upright 55 14 and extends beyond upright 13 to a point over shelf 36. On the latter pro-

jecting end of shaft 55 is fixed an armature 56 in the form of a three-armed spider and a triangular cam piece 57 set so as to have its points a little in advance of the arms of 60 spider 56.

Cam piece 57 is made of insulating material and is of such a size that its corners are adapted to press down the spring arm 45 to bring together contacts 46 and 47. 65

As shown best in Fig. 2, shelf 36 is spaced from upright 13 and the end of core 20 so that the arms of spider 56 may pass between them and these arms are of such length as to pass over the end of the core 20. 70

Spider 56 is preferably of laminated construction and is fairly heavy so as to produce a flywheel effect to carry over the motion from one impulse to the next. 75

The electric circuit through the motor is 75 from one lead 29 to binding post 28 then to coil 21. From the coil the circuit is through connection 60 to binding post 48 on shelf 36 and to contact 47. From the other contact 46 the circuit is through spring arm 45 and 80 connection 61 to binding post 27 and the other lead 29. Bringing together, therefore, the contacts 46 and 47 energizes the coil 21 and magnetizes core 20. This then draws one of the arms of spider 56 over the core, 85 but when the arm is opposite the core the corresponding corner of cam 57 is releasing the contacts and breaking the circuit. Making the armature 56 sufficiently heavy to have a flywheel effect permits it to have 90 sufficient momentum to bring the next arm around far enough to enter the field of influence of the core when a new contact is made.

The present motor is intended chiefly to 95 operate light devices such as toys and advertising devices and a rotating part of one of the latter is indicated at 70, with the motor operatively connected thereto as shown. The connecting means shown consists of a 100 short shaft 71 connected to shaft 55 by means of a universal joint 72 which as shown is a short length of rubber tube. Shaft 71 is supported in a bearing in an upright arm 73 hinged as at 74 to the upright 16 formed on base 11. On the projecting end of shaft 71 is a second piece of rubber tube 75 forming a friction drive element for member 70. In order to hold the parts 70 and 75 together, a small bracket 76 may be secured 105 to base 10 and a spring connected thereto and to hinged arm 73. 110

Having now described the invention and the preferred form of embodiment thereof it is to be understood that the said invention is to be limited not to the specific details herein set forth and illustrated but only by the scope of the claims which follow.

I claim:—

1. An electric motor comprising a base, a single coil horizontally mounted thereon and 10 having a core, a rotatable shaft mounted on said base above said coil and parallel with the core and carrying an armature in the form of a three-armed spider so positioned that rotation of the shaft brings the arms in 15 turn close to one end of said core, means to supply current to said coil and means to complete the circuit therethrough as an arm is approaching said core and to break the circuit as said arm is receding from said 20 core.
2. An electric motor comprising an elongated base having uprights intermediate its ends, a core carried by said uprights and supporting a coil therefor, a shaft rotatable in bearings in said uprights and carrying a 25 three pole armature near one end, said armature

ture poles adapted to pass near one end of said core, a triangular cam also carried by said shaft and having its corners arranged somewhat in advance of said armature poles, 30 spring contacts adapted to be pressed together by said corners, said contacts being in series connection with said coil, and current leads to said coil and contacts respectively.

3. An electric motor comprising an elongated base having uprights intermediate its ends, a core carried by said uprights and supporting a coil therefor, a shaft rotatable in bearings in said uprights and carrying a 40 three pole armature near one end, said armature poles adapted to pass near one end of said core, a triangular cam also carried by said shaft and having its corners arranged somewhat in advance of said armature poles, 45 spring contacts adapted to be pressed together by said corners, said contacts being in series connection with said coil, current leads to said coil and contacts respectively and means at one end of said shaft for 50 transmitting power to a driven device.

WILLIAM G. WAGENHALS.
